J. A. BOUILLON

CARBURETOR

Filed Dec. 17, 1919

INVENTOR:
Jules Adrien Bouillon
By Mr Wallace White
ATTY.

UNITED STATES PATENT OFFICE.

JULES ADRIEN BOUILLON, OF BAZOCHE EN HOULME, FRANCE.

CARBURETOR.

Application filed December 17, 1919. Serial No. 345,513.

To all whom it may concern:

Be it known that I, JULES ADRIEN BOUILLON, citizen of the Republic of France, residing at Bazoches en Houlme, Orne, in the 5 Republic of France, have invented new and useful Improvements in Carburetors, of which the following is a specification.

This invention relates to improvements to carburetors of the kind wherein the spray 10 nozzle is arranged concentrically with the float tank and consists of a carburetor of the aforesaid kind, the construction of which is very simple and adapted to be easily controlled and readily dismounted.

15 The annexed drawing shows by way of example in axial sectional elevation a carburetor constructed in accordance with the invention.

The body or outer casing of the carburetor 20 comprises two hemispherical members namely an upper member *a* constituting the top of the float tank and a lower member *b* constituting the tank proper. These two members are removably secured together by means of 25 a threaded construction.

The lower part *b* of the carburetor casing carries axially a cylinder *c*. The fuel is contained in the annular chamber comprised between the inner surface of tank *b* and the 30 outer surface of cylinder *c*. Said chamber contains the usual float *d* by means of which a constant level is obtained in tank *b*. The float *d*, made of cork or any other suitable material, is pivoted on tank *b* by means of a 35 pin *e* and operates the shank *f* of the needle-valve controlling the inlet tube *g* through which fuel is supplied to the tank, said shank *f* resting upon a spring member *f*¹ rigidly secured to the float. The valve casing *g*¹ is 40 carried by a plate *g*² clamped between the two members *a* and *b*.

The fuel is supplied from the tank to the engine by suction through a horizontal conduit *h* having its inlet near the bottom part 45 of tank *b* and delivering fuel into an axial vertical conduit *h*¹ which is closed at the bottom by a removable cap *h*² and provided at the top with a transverse partition provided centrally with a small opening *h*³. A nozzle 50 member *i* is mounted axially over said opening and constitutes the large sprayer of the carburetor.

The lower end of cylinder *c* is provided 55 with an air inlet valve *k* pivoted to said cylinder and adapted to be closed for slow

running, holes *j* being provided for the passage of air in closed position of said valve.

On the top of cylinder *c* is screwed a tubular member *l* and on the top of the latter is screwed another tubular member *m* tapering 60 upwardly and having lateral openings *m*¹. A wire gauze *v* used for facilitating the thorough mixing of the gases is clamped between the members *l* and *m*.

Into the tapering part of the member *m* 65 extends centrally the lower end of the vertical tubular member *x* formed integrally with the top *a* of the casing, said member comprising an outer part projecting upwardly from the top of the casing and screw-threaded at its upper end *x*¹ for connection with the main suction pipe (not shown) leading to the engine.

The member *m* carries axially by means of a spider *m*² a vertical conduit *n* provided 70 at its lower part with a restricted bore *o*, the inlet end of which is placed over and at a small distance from the outlet opening of the nozzle *i*. This bore *o* constitutes the small sprayer and delivers fuel into conduit *n*. The 75 bottom wall of the latter extends and tapers downwardly so as to form a small casing *p* enclosing both the inlet of the small sprayer *o* and the outlet of the large sprayer *i*, said casing being provided with holes *q* opening 80 into the suction pipe *l* near the restricted part of a Venturi tube *l*¹ formed integrally with tube *l* and at a level situated below the outlet of the sprayer *i*.

85 On the upper end of conduit *n* is slipped 90 the lower end of a tube *r* which is bent laterally and then upwardly and opens into a horizontal conduit *s* provided in the lateral wall of the tubular member *x* thus constituting a low speed bypass.

95 A screw *t* acting as a plug permits of controlling the flow through the tube *r*.

A throttle-valve *u* having its pivot *u*¹ below the outlet of conduit *s* is arranged in 100 the outer part of the tubular member *x*, said throttle-valve being closed for slow running. The throttle valve *u* is operatively connected to the air valve *k* by any suitable means, not shown. An air inlet auxiliary valve *y* is provided for allowing additional air to be 105 admitted in case of a very high suction taking place in the carburetor casing, this air passing through the holes *m*¹.

110 The suction of the engine is indicated by the arrow A and the normal entrance of air

is indicated by the arrow B whereas, as above described, the fuel is admitted through the tube *g* to the float tank.

The operation is as follows:

- 5 During slow running, the valves *u* and *k* are closed. When the engine is on its suction stroke a vacuum is produced above the throttle *u* and acts in the casing *p* through the medium of conduits *s*, tube *r*, conduit *n* and projection *O* of the casing *p*. Hence, a small quantity of air is sucked through the holes *q* into the casing *p* while a small quantity of fuel is sucked into the same from the tube *h* through the nozzle *i*. Said fuel is 10 atomized by the air admitted through the holes *q* and the gaseous mixture passes up through the small sprayer *o*, up through tube *n*, tube *r* and tube *s* and flows thence to the engine.
- 15 In normal running, both valves *u* and *k* being opened, a strong vacuum is produced directly in the cylinder *c*; A jet of fuel issuing from the sprayer *i* strikes the inner faces of casing *p*, is sucked out of said casing through the holes *q* and is then carried upwardly and atomized by the air aspirated directly from outside through the open end of cylinder *c*. The air and fuel are further mixed by the wire gauze *v* on their way to 20 the engine.
- 25
- 30

As clearly set forth in the above description with reference to the drawing, all parts of the improved carburetor including the sprayers may be easily and rapidly taken into pieces by hand.

Having now described my invention, what I claim as new and desire to secure by Letters Patent is:

In a carburetor, the combination of a float tank, a main vertical suction pipe, having a 40 restricted part, a throttle valve in said suction pipe, a fuel nozzle arranged axially in said suction pipe having its outlet orifice above the level of the fuel in the float tank, a casing in which the said fuel nozzle is 45 adapted to extend and provided with an axial tubular projection having its lower orifice placed above and at a small distance from the outlet of said nozzle and means for connecting the upper orifice of said tubular 50 projection to the said suction pipe above the said throttle valve, said casing being provided with lateral holes situated on a lower level than the outlet of the nozzle and opening into said restricted part of the suction 55 pipe.

In testimony whereof I have signed my name to this specification.

JULES ADRIEN BOUILLON.
